(57) **CLAIM**

The ornamental design for a water meter housing, as shown and described.

DESCRIPTION

FIG. 1 is a perspective view of a water meter housing showing our new design;

FIG. 2 is a top plan view thereof;

FIG. 3 is a first side elevational view thereof;

FIG. 4 is a side elevational view of an opposite side from the first side;

FIG. 5 is a bottom plan view thereof;

FIG. 6 is an inlet end view thereof; and,

FIG. 7 is an outlet end view thereof.

The broken line showing is for illustrative purposes only and forms no part of the claimed design.
